(57) **CLAIM**

The ornamental design for a western style boot with a side pocket, as shown and described.

DESCRIPTION

FIG. 1 is a right side elevational view of a western style boot with side pocket, showing my new design.

FIG. 2 is a left side elevational view.

FIG. 3 is a top plan view; and,

FIG. 4 is an enlarged right side perspective view showing the side pocket.

The broken line showing the outline of the boot in FIG. 1-4 is for illustrative purposes only and forms no part of the claimed design.

The current design for a western style boot with side pocket includes a western style boot with a side pocket utilizing a button flap located on the right side of the boot. The boot includes a set of decorative laces in order to present the appearance of a dress shoe.
